UNITED STATES PATENT OFFICE.

JACOB KOBELT, OF HOBOKEN, NEW JERSEY.

EMBROIDERY.

SPECIFICATION forming part of Letters Patent No. 530,595, dated December 11, 1894.

Application filed October 20, 1893. Serial No. 488,697. (No model.)

To all whom it may concern:

Be it known that I, JACOB KOBELT, residing at Hoboken, in the county of Hudson and State of New Jersey, have invented certain new and useful Improvements in Embroidering, of which the following is a specification.

Heretofore, in producing relief work in embroideries, it has been customary to form a basis of underlay stitches, or a cord, and when 10 of stitches such basis may be in the nature of numerous leap stitches on the back of the fabric, which are sometimes produced successively with the embroidery stitches, and over the basis thus formed the embroidery 15 stitches are laid.

It has been found, that to produce a basis from underlay stitches, a too great a quantity of material must necessarily be used, which, while in itself expensive, also requires too 20 much time in the formation thereof, to say nothing of the manifest injury to the fabric by the great quantity of thread penetrations.

My invention has, therefore, primarily for its object to produce, a raised embroidered 25 surface, which will stand out from the fabric, in the form of a hollow ridge or welt.

It has also for its object to provide an embroidery having a relief portion in the nature of a hollow ridge or welt, produced therein, 30 without the aid of a distinct basis of cord or a filling of underlay stitches.

These objects I attain in the manner hereinafter described and claimed, in which, by the use of a single thread carried in successive and peculiar steps, to form both the embroidery and the drawn or back stitches, the hollow portion is produced, and such portion of the fabric held from resuming its normal condition during its ordinary wear or handling.

Referring to the accompanying drawings: Figure 1 is a face view of a piece of fabric produced in accordance with my invention. Fig. 2 is a detail sectional view, greatly enlarged, showing the fabric with an embroidery stitch on the face thereof, before forming the ridge or welt. Fig. 3 is a similar view on the line 3—3 Fig. 1, showing the fabric embroidered and drawn together, showing 45 clearly the hollow welt or ridge. Fig. 4, is a diagrammatic view of a completed section,

greatly enlarged, showing the course or steps.

Referring to the accompanying drawings by letters and numerals, A indicates the fabric, having as shown in Fig. 1, two raised or 55 welt shaped lines or bars B. B' produced in accordance with my invention.

c designates the surface or embroidery stitch and d the back stitch which draws the fabric together.

I am aware that embroidery figures have heretofore been produced by drawing the back or under thread to cause the fabric to gather between the ends of the stitch, and form a ridge or plait, and am also aware that 65 this is usually done by drawing the west threads of the fabric together, they being the most elastic. Embroidery figures produced in this manner, are, however, not well adapted for use on fabrics, subject to stretching after 70 being embroidered, inasmuch as such fabric, in being stretched, soon regains its normal shape, and the ridge thereby flattened out, as no means are provided for holding the gathered or ridge portion to its shape, as would be 75 the case, where a supplemental or basis portion is provided therefor.

One of the essential features of my invention, is to produce a stitch, in which supplemental embroidery portions are provided, 80 which serve as outer reinforce portions, and skirt the main or ridge portion, and effectually prevent the same from being pulled laterally or flattened out when the fabric is pulled transversely to the direction of the 85 embroidery figure.

The embroidered figure on the face of the fabric and the back stitching is produced in the manner most clearly shown in Fig. 4 and the steps taken to produce such figure are 90 best explained as follows: Assuming the lines X—X' on Fig. 4, to indicate the outer edges of the main or ridge portion of the figure and the lines Y.—Y' the outer edge of the skirting or angle portion of such embroidery figure. 95

The thread is secured in the fabric at 1 on the line X, and is then passed diagonally forward over the fabric to the opposite line X' to a point marked 2 making, as it were, a central or ridge embroidery stitch. The thread is then 100 passed diagonally forward and transversely under the fabric from 2 to 3 on the line X, and

up through the fabric; it being at the same time drawn, to cause the fabric to gather or bulge outward between the lines X—X'. The thread is then passed diagonally rearward, 5 transversely over the face of the fabric to a point 4 on the line X', making another embroidery stitch, from whence it passes under the fabric to the point 5 on the line X, Fig. 4 and again drawn. At this point the thread is 10 passed diagonally forward (but in the same direction as before) on the face of the fabric to a point marked 6 on line Y, Fig. 4 forming a supplemental embroidery stitch, which skirts one edge of the hollow or ridge figure. 15 From this point the thread passes under the fabric as a back stitch to a point 7 (practically point 4) and is drawn to crowd the weft inward. It then makes a skirt stitch from 7 to 8, then a back or drawn stitch 8 to 9, 20 from whence it passes as a skirt stitch from 9 to 10 (practically 6) forming in connection with stitch 5 to 6, an angle figure, the strands of which not only draw the weft together but also pull outward against the warp threads, 25 and form thereby a firm stitch which will practically reinforce the central or ridge portion and thereby prevent the same being drawn when the fabric is stretched transversely. After the thread is passed through 30 point 10, it extends as a back stitch to point 11 (practically 2) from whence it passes to 12 and completes an angle portion at the opposite side of the central ridge portion. It then passes back to point 5 as a back stitch, is 35 drawn, and then passes parallel to stitch 1—2, to a point 13, on line X' Fig. 4 which operation completes the first section of the embroidery figure, the same operation being repeated until the required amount of embroidery 40 has been produced.

It will be seen from the foregoing that I wholly complete a single section before proceeding to form the next section, and in the formation of such first section not a single 45 strand of thread is wasted. At the same time three important results are attained: first, the embroidery figure is formed; second, by the peculiar method and manipulation of the stitch, the hollow ridge is produced, and, third, 50 a skirting stitch is also produced which effectually serves as a reinforce for the central or ridge portion and holds it to its shape.

It is obvious that the stitch shown and described, which now forms four regular figures 55 and extending across the face in diagonal lines, may be so modified as to form five or

more figures without departing from the spirit of my invention.

It should be stated that the face or embroidery stitches are held on the face loose, *i. e.*, in 60 contradistinction to the back stitches, so that when the hollow ridge is formed, such face stitches will snugly and smoothly fit over such ridge.

Having thus described my invention, what 65 I claim, and desire to secure by Letters Patent, is—

1. An improved article of embroidery consisting of a piece of fabric having a hollow ridge-like portion, and having figures of embroidery thereon; each figure being composed of central embroidery stitches held over the face of such ridge, and drawn leap stitches on the back held over the hollow of the ridge, and supplemental embroidery stitches skirt- 75 ing the edges of the central or ridge stitches, all substantially as shown, and for the purposes described.

2. An improved article of embroidery consisting of a piece of fabric having a hollow ridge or gathered portion having figures of embroidery thereon, each figure being formed of a single thread and consisting of a loose central portion extended over the face of the ridge, drawn portions extended over the back 80 or hollow portion of such ridge, and supplemental angle-like portions skirting the edges of the central portion, whereby to hold such central stitch portion and the ridge from being drawn out flat, all substantially as shown 85 and described.

3. An improved article of embroidery consisting of a piece of fabric having a hollow ridge or gathered portion having figures of embroidery thereon, formed each of a single 95 thread and consisting of a loose central or face portion, a rear drawn portion or back stitch, and short angle embroidery portions skirting the edges of the central portions; said angle portions having back stitches ex- 100 tended and drawn in opposite diagonal directions, whereby to reinforce and hold the central ridge from spreading laterally, all substantially as shown and described.

Signed at the city of New York, in the 105 county and State of New York, this 19th day of October, 1893.

JACOB KOBELT.
